CLAIM

The ornamental design for a set of fender flares, as shown and described.

DESCRIPTION

FIG. 1 is a top, front and left side perspective view of a right rear fender flare constructed in accordance with the present invention, the corresponding left rear fender flare being substantially a mirror image thereof;

FIG. 2 is a left side elevational view of the right rear fender flare depicted in FIG. 1;

FIG. 3 is a right side elevational view of the right rear fender flare depicted in FIG. 1;

FIG. 4 is a top plan view of the right rear fender flare shown in FIG. 1;

FIG. 5 is a bottom plan view of the right rear fender flare shown in FIG. 1;

FIG. 6 is a rear elevational view of the right rear fender flare of FIG. 1;

FIG. 7 is a front elevational view of the right rear fender flare of FIG. 1;

FIG. 8 is a top, front and left side perspective view of a right front fender flare constructed in accordance with the present invention, the left front fender flare being substantially a mirror image thereof;

FIG. 9 is a left side elevational view of the right front fender flare depicted in FIG. 8;

FIG. 10 is a right side elevational view of the right front fender flare depicted in FIG. 8;

FIG. 11 is a top plan view of the right front fender flare shown in FIG. 8;

FIG. 12 is a bottom plan view of the right front fender flare shown in FIG. 8;

FIG. 13 is a rear elevational view of the right front fender flare of FIG. 8; and,

FIG. 14 is a front elevational view of the right front fender flare of FIG. 8.
